UNITED STATES PATENT OFFICE.

FREDERICK A. FRERICHS, OF PHILADELPHIA, PENNSYLVANIA, ASSIGNOR TO THE HORN & BRANNEN MANUFACTURING CO., INC., OF PHILADELPHIA, PENNSYLVANIA, A CORPORATION OF PENNSYLVANIA.

DESIGN FOR A WALL BRACKET FOR LIGHTING FIXTURES.

Application filed April 23, 1926. Serial No. 17,421. Term of patent 7 years.

To all whom it may concern:

Be it known that I, FREDERICK A. FRERICHS, a citizen of the United States, residing at Philadelphia, in the county of Philadelphia and State of Pennsylvania, have invented a new, original, and ornamental Design for a Wall Bracket for Lighting Fixtures, of which the following is a specification, reference being had to the accompany-

ing drawing, forming part thereof, in which—

Fig. 1 is a plan view;
Fig. 2 is a front elevation.

I claim:

The ornamental design for a wall bracket for lighting fixtures, as shown.

FREDERICK A. FRERICHS.
